UNITED STATES PATENT OFFICE.

ARTHUR M. WALLACE, OF HUNTINGTON PARK, CALIFORNIA.

PARSLEY-DISPLAY HOLDER.

Application filed April 23, 1923. Serial No. 634,057.

My present invention being referred to as of. In the form shown in the drawing, D a parsley display holder, it will be understood that it is a primary object of this invention to provide simple and effective means 5 for spacing and securing parsley or a similar garnish material, as the same is used for decorative purposes in butcher shops, delicatessens, restaurant windows and the like, in which parsley is commonly distributed between and in front of the respective dishes 10 containing meats or other foods for sale; and it should be understood that my invention may be employed for various similar purposes of exhibition or display.

It is a further object of this invention to provide, in addition to suitable plant engaging and supporting elements and securing means therefor, means to facilitate the loading of a parsley display holder of my improved design; and my invention comprises also the method of loading and the methods of employing my display holder hereinafter described, it being a general object of this invention to economize the use of parsley or other display material, to increase the attractiveness of displays of such material, to prolong the life of the material used, and to facilitate the handling thereof.

Other objects of my invention will appear from the following description of a preferred embodiment thereof and from the appended claims, taken in connection with the accompanying drawings, in which—

Figure 1 is a perspective view showing a plurality of dishes suitable for the retention of meats or other food materials within a showcase, the spaces between the respective dishes and in front thereof being occupied by display holders of my improved design, as the same may be used in the handling of parsley.

Fig. 2 is a top plan view of a single, complete holder, one sprig of parsley being shown in place.

Fig. 3 is a vertical section which may be regarded as taken on the line 3—3 of Figure 2.

Fig. 4 is a perspective view showing a loading block suitable for use in the disposing of parsley, or the like, within one of my novel holders, shown with parts broken away.

It is believed that the general character and advantages of my novel parsley holder will be readily understood from the detailed description of a preferred embodiment there-

of. In the form shown in the drawing, D may be regarded as dishes adapted to contain meats or other foods, between or adjacent to which are shown holders H, respectively comprising a pair of parallel, upstanding, stem-engaging elements, one of which may have the character of an angle bar 1, to which the stems of parsley sprigs may be applied in any suitable manner; and the other, 2, having the character of a T bar, adapted to be so applied to the angle bar 1 as to bend the stems of the mentioned sprigs of parsley, or the like, the angle bar 1 and the T bar 2 being thereafter secured to one another by any suitable means, such as the clips 3.

It will be obvious that the mentioned stem-engaging elements, which may advantageously be formed of sheet metal, such as "galvanized iron", and may advantageously be painted green, are adapted to be retained in a vertical position by means of the laterally extending flanges 4 and 5 formed thereon; and to secure the mentioned parts in the relative position best shown in Figures 2 and 3, I prefer to adapt the latching clips 3, shown as pivoted at 6, to permit the stem-engaging elements 1 and 2 to be spaced apart sufficiently to provide for the retention of the stems therebetween, notches 7 being employed for this purpose, and the sheet material of which the members 1 and 2 are formed being sufficiently resilient to accommodate horizontal portions of the mentioned stems.

As best shown in Figure 3, the stem-engaging angle bar 1 may optionally be strengthened by the formation of a bead or return bend 8, at the top thereof, a similar return bend 9 being shown upon the cooperating T bar 2, which is shown as provided with a right angle bend at 10, and with a bend of 180 degrees at 11, whereby this element is strengthened and provided with a flange 13, adapted to underlie the flange 4 of the angle bar with which it cooperates.

In order to load a holder of my novel design, any suitable means may be employed; but I find it advantageous to provide, for this purpose, a loading block 14, shown as provided with a gauging stop 15, and with substantially vertical, stem-spacing projections, which may be mere nails 16, driven through from the bottom thereof at a suitable distance from the edge of the block, this distance being such as to permit of the

retention of an angle bar 1 thereon, in the manner best shown in Figure 4. In order to temporarily hold such an angle bar in position during the distribution of sprigs of 5 parsley therealong, with the stems of said sprigs overlying the angle bar in the manner shown, any suitable retaining means may be provided, and for this purpose I prefer to employ an upstanding pin or projection 17, which may be a mere nail driven so near to the edge of the block 14 as to adapt the same to extend through a hole 18 in the mentioned angle bar.

When sprigs of parsley, or the like, have 15 been distributed along the block 14 in the manner described, the separation and retention of the respective sprigs being facilitated by the mentioned projections 16, the T bar 2 may be so applied as to bend the 20 mentioned stems 19 from the position shown at the left of Figure 4, into the position shown at the right of said figure; and, the bars 1 and 2 being then locked together by means of the clips 3, the holders and the 25 parsley engaged thereby may be lifted from the loading block 14 and employed for the intended purpose of display.

As will be obvious from an inspection of Figures 2 and 3, the edges 20 of my holder 30 may be employed as a guide in cutting off the ends of the stems of the parsley, after the same have been secured in the manner described.

By means of a holder of the character 35 above described, a relatively small quantity of parsley, not exceeding one-third of the quantity heretofore commonly used, may be so disposed as to secure a decorative effect distinctly superior to that which has heretofore customarily been obtained, and it will 40 be obvious that the distribution of the parsley may be very quickly effected and that, although it is not liable to easy derangement, by withdrawal of a dish or otherwise, 45 the respective holders and the parsley retained thereby may be quickly removed from a showcase or a counter when desired, as at the end of the day's business, and as quickly restored to place.

50 My device, moreover, affords not only a convenient means for the distribution and support of parsley, or the like, but it also facilitates the preservation of the parsley in good condition, it being advantageous to 55 assemble the holders, at the end of a day's business, and to provide moisture for the parsley, either by sprinkling the same or by immersing the bases of the respective holders, through which the stems of the parsley 60 may extend horizontally, in water.

Although I have herein described but one embodiment, it will be understood that various features thereof might be independently employed, and also that various modifications might be made therein without departure from the spirit and scope of my invention, as the same is indicated above and in the following claims.

What I claim is:

1. A display holder comprising a pair of 70 upstanding elements between which is retained the article to be displayed, one of said elements having a lateral flange and pivoted clips mounted upon said lateral flange, said clips adapted to embrace both 75 sides of said lateral flange and engage the other element.

2. A display holder comprising a pair of upright elements, one of said elements having lateral flanges extending upon both 80 sides thereof, the other of said elements having a lateral flange adapted to rest upon one of the lateral flanges of the first element, and means for detachably securing said elements together.

3. A display holder comprising a pair of upright elements, one of said elements having lateral flanges extending upon both 90 sides thereof, the other of said elements having a lateral flange adapted to rest upon one of the lateral flanges of the first element and pivoted clips carried by the first mentioned element adapted to engage the second element.

4. A display holder comprising a pair of 95 upright elements, one of said elements having lateral flanges extending upon both sides thereof, the other of said elements having a lateral flange adapted to rest upon one of the lateral flanges of the first element, and notched pivoted clips carried by 100 the first element adapted to embrace the flanges of both of said elements.

5. A display holder comprising an angle bar and a T bar, the legs of said angle bar 105 being adapted to engage one horizontal leg and the vertical leg of said T bar and means for clamping said bars together.

6. A display holder comprising an angle bar and a T bar, the legs of said angle bar 110 being adapted to engage one horizontal leg and the vertical leg of said T bar and means for clamping said bars together, an aperture formed in the upright legs of said bar and fastening means extending through 115 said aperture for temporarily holding said legs apart.

In testimony whereof I have signed my name to this specification.

ARTHUR M. WALLACE.
